UNITED STATES PATENT OFFICE.

ELMER E. SHIPLEY, OF WASHINGTON, DISTRICT OF COLUMBIA.

WINDOW-CLEANER.

1,120,094.

Specification of Letters Patent.

Patented Dec. 8, 1914.

Application filed March 21, 1914. Serial No. 826,288.

To all whom it may concern:

Be it known that I, ELMER E. SHIPLEY, a citizen of the United States, residing at Washington, in the District of Columbia, have invented certain new and useful Improvements in Window-Cleaners, of which the following is a specification.

This invention relates to new and useful improvements in window cleaners, and more particularly to a novel construction, designed to remain attached to either or both sides of a window, in such position that the raising or lowering of the sashes, cleans the glass panels.

An object of this invention is the provision of a window cleaner, which also serves the purpose of a weather strip, to prevent the entrance of air between the sashes, and further to engage the panels with sufficient resiliency to act in the capacity of a window silencer, preventing the rattling of the sashes, whether opened, closed or in any position.

A further object of this invention is the provision of a device of the type specified, which will be comparatively simple and inexpensive to manufacture, reliable and efficient in use, and readily operated.

With the above and other objects in view, this invention resides in the novel features of construction, formations and arrangements of parts to be hereinafter fully more described, claimed and illustrated in the accompanying drawings in which:

Figure 1 is a transverse sectional view taken through a window frame, with my invention applied thereto, showing the sashes in their normal positions. Fig. 2 is a similar view of the lower portion of the frame showing the upper sash lowered. Fig. 3 is a detail sectional view of a portion of the window with the upper member of the lower sash in normal position and the upper member of the upper sash in a partly lowered position. Fig. 4 is a horizontal sectional view taken through the frame, showing my invention in plan view. Fig. 5 is a detail transverse sectional view of the telescoping casing and cleaning strip. Fig. 6 is a detail perspective view of one of the brackets. Fig. 7 is a modified form of casing adapted for window sashes having parting strips.

Referring to the accompanying drawings by similar characters of reference, the numeral 1 denotes in general a window frame, comprising the upper and lower rails 2 and

3, connected at their ends by the vertical side rails 4, the latter of which are provided with the customary sash guides 5, in which are slidably located the upper and lower 60 sashes 6 and 7. These said sashes 6 and 7 have the usual glass panels 8, mounted therein and fastened against displacement by any suitable means.

Brackets 9 and 10, are secured to the inner sides of the rails 4 and lower side of the sash 6 respectively, upon the outer side of the window frame, as clearly shown in the drawings. If desired, similar brackets (not shown in the drawings) can be attached to the rails 4 and sash 6, within a room, but as the construction will be identical with the following description, it is thought that the description of but one set will be sufficient.

Horizontal arms 11 project from the brackets 9 and 10, and have hinged thereto as at 12, movable supporting rods 13, which are yieldingly forced upwardly to a horizontal position by the coil springs 14. 80 These rods are provided with fingers 15 and 16 arranged to contact with the underside of the arm 11, thereby limiting the upward movement of the said rods. A telescoping casing 17, formed with ears 18 85 for sliding engagement with the rods 13, is slidable upon the latter and normally forced in the direction of the panels 8, by the retractile springs 19, which are secured to the said ears 18 and fingers 16 respectively. 90 The ears 18 are formed with sleeves 18^a to prevent the ears from binding upon the movement of the casing 17.

An adjustable clamp 20 is disposed within the telescoping sections of the casing 17, 95 and retained against displacement by the locking screws 21, which extend through the slots 22, formed in the casing 17, and engage the threaded openings 23, formed in the said clamp. Owing to this specific construction, it is possible to adjust the clamp to and from the panel 8 as the strip 24, formed from felt or the like becomes worn. As shown in Fig. 5, this strip 24 is reversible so that when one side becomes too worn 105 to be remedied by the adjustment of the clamp, the latter can be reversed. Rollers or putty engaging members 25 are journaled upon the ends of the casings 17, for a purpose to be later explained.

Referring more particularly to Fig. 7 of the drawing, the edges of the telescoping

sections of the casing are notched as at 27, to accommodate the parting strip of a window sash (not shown in the drawings).

- The operation of the device is as follows:
- 5 When the operator desires to clean the panels 8, the upper sash is grasped firmly by handles (not shown which can be attached thereto) and raised and lowered with the desired rapidity. The strip 24 which is obviously forced by the springs into engagement with the said panels, passes over the latter cleaning them. In cases where the panels are very dirty, a little water can be applied to the same which will be taken up by the strip 24 and spread over the window.
  - 10 As the rollers 25, which are spaced slightly from the panels during this operation, reach the upper rail of the upper sash and lower rail of the lower sash, they obviously swing the casings 17 outwardly against the tension of the springs and prevent injury to the various operating parts in the event of rapid operation, while as a further preventative of injury to the casings carried by the upper sash, the roller by its upwardly rigid connection with the brackets 9, through the arm 11 and fingers 15 and 16, contacts with the lower rail 3, thereby preventing the casing from contacting therewith.
  - 15 A packing strip 26 of felt or the like is secured to the upper side of the casing 17 carried by the sash 8, and when the sashes are in their normal positions as shown in Fig. 1, the said strip 26 is forced by the springs to seal the space between the meeting ends of the said sashes against the entrance of air.
  - 20 The resiliency of the springs is sufficiently strong to hold the sashes rigidly relative to the frame and to each other, thereby acting as a window silencer and eliminating all noise of rattling, when the windows are in any position.
  - 25 It should be understood in this connection, that various minor changes in the specific details of construction, can be resorted to within the scope of the appended claims, without departing from or sacrificing any of the advantages of the invention, and that
  - 30 while, for the purpose of illustrating I have shown my device in connection with the window of a building, I do not wish to be limited to such use alone, but may employ the same in connection with any other structure to which the various parts will adapt themselves, such as show cases, car windows and the like.
  - 35 From the foregoing disclosures taken in connection with the accompanying drawings, it will be manifest that a window cleaner is provided which will fulfil all the necessary requirements of such a device.

Having thus fully described this invention, what I claim as new and desire to protect by Letters Patent is:

1. In a window cleaner, a casing, a reversible cleaning strip carried thereby, and putty engaging means for guiding said strips over the contacting puttied edges of the window.
2. In a window cleaner, bodily movable supporting brackets, a laterally yieldable casing hinged thereto, and a cleaning strip carried by the casing to engage the panels of a window.
3. In a window cleaner, supporting brackets, rods movably connected thereto, a casing movably connected to the said rods, means for yieldingly forcing the casing in a given direction, and a strip adjustably supported within said casing and projecting therefrom, as and for the purposes set forth.
4. In a window cleaner, supporting brackets, arms extending therefrom, rods hinged to said arms and yieldingly connected to the latter, means for limiting the hinged movement of the rods, a casing slideable upon said rods and yieldingly forced in a given direction, a strip adjustable within said casing and extending therefrom to engage the panels of a window, and rollers carried by said casing as and for the purposes set forth.
5. In a window cleaner a plurality of supporting brackets, arms extending therefrom, supporting rods hinged to said arms, fingers formed upon said rods to engage the arms and limit the upward movement of the rods, springs connecting said rods and arms and normally forcing the rods upwardly, a telescoping casing slideable upon said rods, springs for forcing the casing toward the inner ends of the rods, a clamp adjustable within the casing and a reversible strip carried by the clamp and designed to engage the panels of a window and rollers carried by the casing as and for the purposes set forth.
6. In a device of the character described, for use in connection with a window frame and its sashes, brackets secured to the frame and certain of said sashes, casings adjustable in said brackets, strips mounted in said casings, said strips designed to clean a plurality of window sashes upon the movement of one sash, and rollers carried by the casings, as and for the purposes set forth.

In testimony whereof I affix my signature in presence of two witnesses.

ELMER E. SHIPLEY.
